DESIGN FOR A SPOON.

SPECIFICATION forming part of Design No. 20,683, dated April 21, 1891.

Application filed March 14, 1891. Serial No. 385,132. Term of patent 3½ years.

To all whom it may concern:

Be it known that I, ROLLA W. HESS, of St. Louis, Missouri, have invented and produced a new and original Design for Spoons, of which 5 the following is a specification, reference being had to the accompanying drawing, forming part thereof, and which is a face-view of the newly-designed spoon.

The invention relates more especially to 10 the bowl of the spoon; and the leading feature of the design consists in the representation of the veiled face *a* of the personage

popularly known as the "Veiled Prophet," of St. Louis, and which is produced, more or less, in relief in the bowl *c*, which otherwise, as 15 well as the stem *d* of the spoon, may be finished in any style fancy may dictate.

I claim—

The design for a spoon, as shown and described.
